UNITED STATES PATENT OFFICE.

GEORGE W. PERKS, OF AKRON, OHIO, ASSIGNOR TO THE GEORGE W. PERKS COMPANY, OF AKRON, OHIO, A CORPORATION OF OHIO.

MOUNTING FOR ABRASIVE WHEELS OR THE LIKE.

Application filed November 22, 1926. Serial No. 149,829.

This invention relates to a new and improved form of mounting for abrasive wheels or similar objects, the specific purpose of the invention being to provide an improved 5 clamping device for a wheel of this type which will securely hold and clamp a wheel so that in the event of fracture the sections or fragments of the wheel will be retained and will not fly out. With the use of the present 10 invention, it is possible to safely and securely clamp the abrasive wheel by means which will insure the safe operation thereof at high speeds.

The surfaces of abrasive wheels are irregular, being formed with numerous minute elevations and depressions and the invention utilizes a form of clamping plate or disk which will securely grip the rough surfaces of the wheels. The specific description of the 20 invention will be given in connection with drawings illustrating preferred forms of the invention.

Figure 1 is a side elevation of an abrasive wheel;

25 Figure 2 is a section through the center of the wheel.

Figure 3 is an enlarged view of a section of the wheel and a clamping plate; and

30 Figure 4 is a view similar to Figure 3 but showing a modified form thereof.

In the drawings, the numeral 1 represents the usual power shaft upon which the abrasive wheel 2 is mounted, the form shown in Figures 1 to 3 inclusive including two 35 clamping plates 3 mounted on either side of the wheel and clamped securely by a nut 4. These plates are preferably formed with raised annular bearing surfaces 5 about thin outer peripheries so that the pressure is concentrated near the periphery of the wheel. Between the plates and the wheel are placed 40 thin metallic disks or secondary plates 6, the surfaces of the disks which contact the wheel being provided with minute irregularities or 45 elevations and depressions which correspond to and are commensurate with the irregularities on the surface of the wheel. Figure 3 is an enlarged view in which the irregularities upon the wheel and in the surface of the 50 disks have been magnified to such an extent as to illustrate the manner in which the elevations and depressions mesh when the pressure is applied to the clamping plates.

The operation of the device will be apparent 55 from the description and disclosure which

has been given, it being noted that the interlocking of the two roughened surfaces gives a firm anchorage for the wheel, and fragments or sections thereof cannot fly out of the mounting.

60 The roughened surfaces upon the disks may be obtained in a number of ways, for example, by knurling, or cutting a fine groove or grooves in the face of the disk. A spiral groove, such as found upon the surface of a phonograph disk, has been found to operate satisfactorily for the purpose. The depths and extent of the irregularities may be varied but should preferably be comparable to the depths and extent of the irregularities upon 65 the face of the wheel so a substantially complete nesting will be obtained.

In the form shown in Figure 4, the irregularities or projections and depressions are formed directly upon the surface of the 70 clamping plate 3, rather than upon a separate disk. This form of invention will operate in the same manner as the other form shown. The former is suitable for use with old wheel 75 mountings.

80 Attempts have been made in the prior art to secure an effective mounting providing roughened clamping plates, but these have not been entirely successful, because the plates have been roughened without regard 85 to the roughness of the stone or wheel, and the result has been that the frictional contact between the plates and the wheel has been lessened rather than increased by the roughness, or the stone has been weakened by 90 grooving it deeply to receive the projections on the plate.

95 It has also been proposed to use clamping plates of comparatively soft materials, such as lead or wood, but these have not been so effective because the projections on the faces of a broken part of a stone will pull through this material under the action of centrifugal force.

100 It is to be understood that the present invention is directed to the use of the usual clamping plates or washers most generally of steel or other comparatively hard material and preformed by roughening in such a way 105 that its projections can mate with the characteristic recesses of the face of an abrasive wheel.

105 What is claimed is:

110 1. A mounting for abrasive wheels, comprising a comparatively hard plate having

preformed minute irregularities corresponding substantially to the minute irregularities characteristic of the surface of the wheel, and means to clamp the plate and wheel together so that the irregularities will mate and thereby securely retain the wheel in position when clamping pressure is applied.

2. A mounting for abrasive wheels, comprising a comparatively hard plate having minute irregularities corresponding substantially to the minute irregularities characteristic of the surface of the wheel, and means to clamp the plate and wheel together so that the irregularities will mate and thereby securely retain the wheel in position when clamping pressure is applied, the pressure being confined to narrow annular bands adjacent the periphery of the wheel.

3. The combination with an abrasive wheel having characteristic minute elevations and depressions in its surface, of a comparatively hard metallic plate having preformed minute elevations and depressions in its surface placed against the surface of the wheel, and

means to exert clamping pressure thereon for causing interlocking of such elevations and depressions.

4. The combination with an abrasive wheel having characteristic minute elevations and depressions in its surface, of a comparatively hard metallic plate having preformed minute elevations and depressions in its surface placed against the surface of the wheel, and means to exert clamping pressure thereon in narrow annular bands adjacent the periphery of the wheel for causing interlocking of such elevations and depressions.

5. A mounting for abrasive wheels, comprising a comparatively hard plate having preformed minute irregularities comparable with the characteristic irregularities of the surface of the wheel, and means to clamp the plate and wheel together so that the irregularities will mate and thereby securely retain the wheel in position when clamping pressure is applied.

GEORGE W. PERKS.
